GARMENT HANGER

Victor H. Pechtel, Farmingdale, N. Y.

Application October 3, 1947, Serial No. 777,731

5 Claims. (Cl. 223—91)

1

This invention relates to garment hangers, and especially to a combination coat and trousers hanger wherein the trousers or other garment can be suspended in an inverted position.

In the manufacture of garment hangers of the variety mentioned, it is necessary that the construction thereof be simple and that the hanger be economical to manufacture. It also is desirable to have a construction that will allow easy placing and removal of garments thereon. The clips need to be arranged so that they can be operated to grasp with facility and hold the garment.

One of the objects of the present invention is to provide an improved garment hanger which may be made economically, which is strong, and which will provide for the easy placing and removal of garments relative thereto.

Another object of the invention is to provide a combination coat and garment hanger which can be stored in a minimum of space.

One of the features of the invention is to provide a coat hanger structure which is engageable with the ends of a central tubular member, the tubular member being adapted to slidably carry garment holding clips. A pair of clips are mounted on each end of the tubular member, said clips being in two parts and held on the tubular member by means of a common spring. In a preferred form, the spring is circular and the ends are held in place in depressions struck in said clips. Segmental circular surfaces on the shaped clips frictionally engage the tubular member so that the clip may be slid longitudinally relative to the tubular member and will remain in any desired adjusted position. A spring or pair of springs can be placed inside of the tubular member and the ends of said spring or springs arranged to engage a pin extending inwardly from each of the clips or a plug attached to the pin. The spring or springs will serve to urge the clips outwardly relative to each other so that a garment engaged and held by the clips will be held in a stretched condition.

Another feature of the invention is the split wire hook hinged to the coat hanger wire. The hook is arranged so that it can be folded back on itself on the wire and thus conserve space when it is desired to store the hanger in a place such as a drawer or suitcase. The inturned ends of the coat hanger portion can be made to fit into apertures in the end of the central tube member and to be detachable therefrom so that the tube can be separated from the coat hanger portion and placed in relation thereto in a drawer or suitcase so as further to conserve space.

In the preferred form of the invention, the parts are made of metal, such as aluminum, steel, brass or any other desired material.

Other objects, advantages, and features of the invention will become apparent from the following description and drawings which are merely exemplary.

In the drawings:

Fig. 1 is an elevation view of an assembled hanger;

Fig. 2 is a side view of the hanger;

Fig. 3 is an exploded detail view of one of the clips;

Fig. 4 is a sectional view taken along the line 4—4 of Fig. 1;

Fig. 5 is an enlarged fragmentary sectional view taken along the line 5—5 of Fig. 1, the wire being shown in full;

Fig. 6 is an exploded view of the hanger with the parts disengaged and the hook folded back on the coat hanger portion.

In a preferred form of the invention, the coat hanger portion may be made from a bent piece of wire 10 made of aluminum, steel, or other material of a suitable stiffness. The wire can be bent to provide integrally extending portions 11 and a ring 12 to which the hook 13 is attached. The hook is formed from wire and twisted as shown, the hook portion having the wire separated to form a space 13' at least as wide as the diameter of wire 10 so that the hook can be folded as seen in A in Fig. 6.

A central tube 14 of aluminum or other suitable material is provided and slots 15 formed in each end thereof for the purpose to be discussed hereafter. In a preferred form of construction, a plug 16 (Figs. 1, 5) having an enlarged head 17 is made to fit into the ends of the tubular member 14. The plugs can have apertures 16' therein to receive the ends 11 of the coat hanging wire 10. It is, of course, apparent that other means may be used for holding the ends of the wire 11 in the tubular member 14.

Each of the clips is composed of a member 18 preferably stamped from a flat piece of metal, the arcuate portion 19 of each being of the correct radius to encircle and snugly engage tube 14. The split arcuate spring 20 is inserted

through opening 21 of the clips, said spring holding the clips slidably in place on the tubular member 14. The ends 18' of the clips 18 may be roughened so as to assist the clip to grasp the garment more firmly. The ends of the clip members may be bent toward each other (not shown) to facilitate gripping the garment and also to facilitate entrance of the clip into the cuff thereof. A depression 22 is formed or struck out from the body of the clip 18 for the purpose of receiving and holding the ends of the springs 20 in place particularly from side movement.

A pin 23 is inserted in one of each of the pairs of clips and through the respective slot 15. The inner end of said pin 23 preferably enters a hole 23B in plug 16, said

pin 23 being held in place by a lock washer 24.

plug in turn being engaged by the outer ends 24 of the springs 25.

In the form of the invention shown, a central separator 26 may be used, or in place thereof, a single spring extending the entire length of the tube 14 of course can be employed.

In use with trousers, for example, one pair of clips can be separated and one side of each inserted into each cuff or pants leg. Then the other clip can be pressed toward the first clip, 10 the clip element separated and inserted into each cuff in a similar manner. Upon releasing the clips, it will be evident that the trousers will be grasped and will be stretched by the springs 25 or the resilient means used in the tubular member.

When it is desired to carry the combination garment hanger in a suit case or store the same in a drawer, the hook may be folded back on the wire as seen in Fig. 6 and the tube disengaged from the coat hanger wire. The tube then can be laid upon the coat hanger wire or stored elsewhere.

One form of device has been illustrated but it is apparent that other details of construction and combination of parts can be employed without departing from the invention except as set forth in the appended claims.

I claim:

1. A garment hanger comprising a central tubular member, hanging means connected to said central tubular member, a garment clip slidably mounted on said tubular member adjacent each end of said tubular member, and frictionally engaging the same, spring means carried by said tubular member, and connections between said clips and said spring means, said spring means acting on said connections and normally urging said clips outwardly relative to each other so that a garment mounted thereon will be held in a stretched position.

2. A garment hanger comprising a central tubular member, hanging means connected to said central tubular member, a pair of spring pressed garment holding clips slidably mounted on the exterior of and adjacent each end of said tubular member and frictionally engaging the same, a pair of springs mounted in said tubular member, a central separator between said springs, and connections between said clips and outer portions of said springs, said springs acting on said connections and normally urging said clips outwardly relative to each other on said tubular member, so that a garment mounted thereon will be held in a stretched position.

3. A garment hanger comprising a central tubular member having longitudinally extending slots adjacent each end thereof, hanging means connected to said central tubular member, a pair

of spring pressed garment holding clips slidably mounted on the exterior of and adjacent each end of said tubular member and frictionally engaging the same, spring means within said tubular member, connections extending into said slots from each of said exteriorly mounted clips engaging the outer ends of said spring means, said spring means acting on said connections and normally urging said clips outwardly relative to each other on said tubular member, said slots guiding the movement of said clips.

4. A garment hanger comprising a central tubular member, a coat hanger frame having end portions engaging the ends of said central tubular member, a pair of spring pressed garment holding clips slidably mounted adjacent each end of said tubular member and frictionally engaging the same, yieldable means carried in said tubular member, and connections between said slideable clips and said yieldable means, said yieldable means acting on said connections and normally urging said clips outwardly relative to each other on said tubular member, so that a garment mounted thereon will be held in a stretched position.

5. A combination garment hanger comprising a central tubular member having longitudinally extending slots adjacent each end thereof, a coat hanger frame having inturned end portions engaging the ends of said central tubular member, a pair of spring pressed garment holding clips slidably mounted on and adjacent each end of said tubular member and frictionally engaging the same, spring means within said tubular member, connections extending into said slots from each of said clips engaging the outer ends of said spring means, said yieldable means acting on said connections and normally urging said clips outwardly relative to each other on said tubular member, said slots guiding the movement of said clips.
